UNITED STATES PATENT OFFICE

167,010

CLOCKCASE

Rebecca Louise Thompson, Arlington, Vt.

Application March 21, 1952, Serial No. 18,989

Term of patent 3½ years

(Cl. D42—7)

To all whom it may concern:

Be it known that I, Rebecca Louise Thompson, a citizen of the United States of America, residing at Arlington, county of Bennington, State of Vermont, have invented a new, original, and ornamental Design for a Clock Case, of which the following is a specification, reference being had to the accompanying drawing, forming a part hereof.

I claim:

The ornamental design for a clock case, as shown, and described.

REBECCA LOUISE THOMPSON.
